UNITED STATES PATENT OFFICE

138,279

DESIGN FOR A BOTTLE

George Grunberg, New York, N. Y., assignor to
The G. G. Patent Company, Cincinnati, Ohio, a corporation of Ohio

Application May 2, 1944, Serial No. 113,428

Term of patent 7 years

(Cl. D58—8)

To all whom it may concern:

Be it known that I, George Grunberg, a citizen of the United States, residing at New York city, in the Borough of Manhattan, county of New York, and State of New York, have invented a new, original, and ornamental Design for a Bottle, of which the following is a specification, reference being had to the accompanying drawing, forming a part thereof.

I claim:

The ornamental design for a bottle, substantially as shown.

GEORGE GRUNBERG.
